BOTTOM DUMPING CEMENT BAILER

Aden F. Sorben, Long Beach, Calif.

Application April 5, 1939, Serial No. 266,193

6 Claims. (Cl. 166—19)

This invention relates to a bottom dumping bailey, particularly adapted to place cement in an oil well.

An object of my invention is to provide a novel bottom valve dump bailey, which is simple in construction and effective in operation.

Another object is to provide a novel bottom valve dump bailey, which is provided with a novel means of unlatching the bottom valve or gate for the purpose of releasing the load of cement, or the like, within the bailey.

Another object of my invention is to provide a novel bottom valve dump bailey, in which the releasing valve or gate is actuated by a longitudinal movement of the bailey within the well.

Other objects, advantages and features of invention may appear from the accompanying drawing, the subjoined detailed description, and the appended claims.

20 In the drawing—

Figure 1 is a longitudinal, sectional view of my bailey in closed position.

Figure 2 is a fragmentary, longitudinal, sectional view of my bailey in open position.

25 Figure 3 is a sectional view taken on line 3—3 of Figure 2.

Figure 4 is a plan view of the bottom valve or gate.

Referring more particularly to the drawing, 30 the bailey 1 is mounted on the lower end of pipe or tubing 2. The bailey 1 consists of a tubular housing 3 of considerable length, and is adapted to retain a quantity of material, such as cement. The bottom of the housing is closed by a valve or 35 gate 4, which is hingedly mounted on one side, as shown at 5. The valve is held in closed position by a spring finger 6, which is fixedly attached to the outside of the housing 3, and is preferably counter-sunk into the housing so that the outer 40 surface of the spring finger is flush with the outside of the housing. A lug 7 on the lower end of the finger 6 normally engages the eye 8 on the valve 4, as shown in Figure 1. When the spring finger thus engages the valve, the valve 45 is held closed and will remain closed until the spring finger is tripped inwardly and disengaged from the eye 8, as will be further described.

A pair of collars 9, 10 are slidably mounted on the housing 3 and are held in spaced relation 50 by a plurality of springs 11. One of the springs 12 is fixedly attached to the lower collar 10 but the upper end of this spring is free to move inwardly and outwardly as tension is applied to the springs. A spring catch 13 is fixedly attached at its lower end to the outside of the

housing 3, the upper end of this spring catch normally flexing outwardly to enter a slot 14 in the collar 9, and thus hold the collars and the springs against downward movement. When the bailey reaches the lower casing or bore of the well 15, the spring fingers 11, 12 will be compressed, since the lower part of an oil well is always of lesser diameter than the upper part of the well.

While running into the bored hole or casing, 10 the upper collar 9 engages the coupling 16, thus limiting the upward movement of the collar and spring finger assembly. When the smaller diameter in the well is reached, the spring 12, 15 and particularly the upper portion thereof, will be pressed inwardly and will enter the slot 14. The operator now pulls the pipe and the bailey upwardly, and due to the frictional resistance of the springs 11, 12, the collars 9, 10 will remain stationary, and the housing 3 will be pulled upwardly through these collars. The upper end of the spring 12 will press the upper end of the spring catch 13 inwardly, thus permitting the collar 9 to pass the spring 13 and continue to move downwardly. Further upward movement 20 of the housing 3 will cause the collar 10 to engage the spring finger 7, as shown in Figure 2, thereby disengaging the spring finger from the eye 8 and permitting the valve or gate 4 to swing 25 downwardly, thereby releasing the load of cement, or the like, in the bailey. The bailey is now returned to the surface, is again loaded, 30 and the operation is repeated, if necessary.

Having described my invention, I claim:

1. A bottom dumping bailey comprising a tubular housing, a gate pivotally mounted on the lower end of the housing and adapted to close the same, a spring finger engageable with the gate to hold the same in closed position, a pair of spaced collars slidably mounted on the housing, a plurality of spring arms attached to and connecting the collars, the lowermost collar being adapted and arranged to engage the spring finger and release said finger from the gate, whereby said gate is released.

2. A bottom dumping bailey comprising a tubular housing, a gate pivotally mounted on the lower end of the housing and adapted to close the same, a spring finger engageable with the gate to hold the same in closed position, a pair of spaced collars slidably mounted on the housing, a plurality of spring arms attached to and connecting the collars, the lowermost collar being adapted and arranged to engage the spring finger and release said finger from the gate, where-

by said gate is released, a spring catch mounted on the housing and adapted to engage one of said collars, one end of one of said spring arms being free and adapted to engage and release said spring catch when said spring arms are compressed.

3. A bottom dumping bailer comprising a housing, a gate hingedly mounted on the lower end of the housing, a spring finger releasably engaging the gate and adapted to hold said gate in closed position, said spring finger comprising a leaf spring attached to the outside of the housing, a spring catch comprising a leaf spring attached to the outside of the housing and spaced from the spring finger, a pair of spaced collars slidably mounted on the housing, a plurality of spring fingers connecting said collars, one of said spring fingers being free at the upper end and engageable with the spring catch to release the same when the spring arms are compressed, the lowermost collar engaging the spring finger to release the same on relative longitudinal movement of the collar and housing.

4. A bottom dumping bailer comprising a tubular housing, a gate pivotally mounted on the bottom end of the housing and adapted to close the same, a spring finger fixedly attached at one end to the housing, the free end of said spring finger engaging the gate to hold the same in closed position, a pair of spaced collars slidably mounted on the housing, a plurality of spring arms attached to and connecting the collars, the lowermost collar being adapted and arranged to engage the spring finger and release said finger from the gate, whereby said gate is released to swing into open position, a spring catch engageable with one of said collars, one end of one of said spring arms being free and adapted to engage and release said spring catch when said spring arms are compressed.

from the gate, whereby said gate is released to swing into open position.

5. A bottom dumping bailer comprising a tubular housing, a gate pivotally mounted on the bottom end of the housing and adapted to close the same, a spring finger fixedly attached at one end to the housing, the free end of said spring finger engaging the gate to hold the same in closed position, a pair of spaced collars slidably mounted on the housing, a plurality of spring arms attached to and connecting the collars, the lowermost collar being adapted and arranged to engage the spring finger and release said finger from the gate, whereby said gate is released to swing into open position, a spring catch engageable with one of said collars, one end of one of said spring arms being free and adapted to engage and release said spring catch when said spring arms are compressed.

6. A bottom dumping bailer comprising a housing, a pair of spaced collars slidably mounted on the housing, springs connecting the collars, said springs being adapted and arranged to bear against the bore or casing of a well, a gate pivotally mounted on the lower end of the housing, latch means engaging the gate, a spring catch engaging one of said collars, one end of one of said springs being free and adapted to engage and release said spring catch when the springs are compressed, one of said collars engaging said latch means on relative longitudinal movement of the collar and housing to disengage the latch means and release the gate.
